DESIGN FOR A HEAD FOR A HAND MIRROR OR SIMILAR ARTICLE

Leo Marder, Brooklyn, N. Y.

Application October 10, 1940, Serial No. 95,742

Term of patent 3½ years

To all whom it may concern:

Be it known that I, Leo Marder, a citizen of the United States and a resident of Brooklyn, in the county of Kings and State of New York, have invented a new, original, and ornamental Design for a Head for a Hand Mirror or Similar Article, as shown, of which the following is a specification, reference being had to the accompanying drawing, forming a part thereof.

Figure 1 is a plan view of a head for a hand mirror or similar article showing my new design;

Figure 2 is a section taken on the line 2—2 of Figure 1.

The dominant features of my design reside in the portion shown in the full lines constituting the back panel of a head of a hand mirror. The design is also adapted for use as a head for hand brushes.

The shading on the drawing indicates a contrasted color appearance.

I claim:

The ornamental design for a head for a hand mirror or similar article, substantially as shown and described.

LEO MARDER.
